UNITED STATES PATENT OFFICE.

THEODORE AHLBORN, OF WATERLOO, IOWA, ASSIGNOR TO THE WATERLOO CEMENT MACHINERY CORPORATION, OF WATERLOO, IOWA.

CONCRETE-MIXER.

1,052,998.

Specification of Letters Patent. Patented Feb. 11, 1913.

Application filed May 24, 1912. Serial No. 699,522.

To all whom it may concern:

Be it known that I, THEODORE AHLBORN, a citizen of the United States of America, and a resident of Waterloo, Blackhawk county, 5 Iowa, have invented certain new and useful Improvements in Concrete-Mixers, of which the following is a specification.

My invention relates to improvements in concrete mixers, and the object of my improvement is to simplify and expedite the mixing operation, by securing a coaxial delivery drum in combination with the mixing drum, having turbinated or whirled blades adapted to receive and deliver into the mixing drum the dry unmixed materials or components of the concrete. This object I have accomplished by the means which are hereinafter described and claimed, and which are illustrated in the accompanying drawings, in which:

Figure 1 is a vertical longitudinal axial section of my improved mixing-drum with its delivery drum attachment. Fig. 2 is a rear elevation of the delivery drum, with 25 the rear annular face thereof sectioned away. Fig. 3 is a front elevation of said delivery-drum, with its forward annular face sectioned away.

Similar numerals of reference denote corresponding parts throughout the several views.

Referring first to Fig. 1, this view shows the hollow cylindrical mixing-drum 1 having a rim-gear 15 thereabout adapted to be 35 rotated with said drum by means of some prime-mover and a suitable power transmission device not shown. The drum is mounted on anti-friction wheels 6, and has in its front face an axial opening adapted 40 to receive a projecting chute 4, the latter being supported by the forward uprights 7 of the machine-frame. To the inner end of said chute 4 is pivoted a swinging section 5, which may be tilted forward or back by 45 means of a hand-lever and connections, to either close the chute, or to direct the contents of the drum outwardly through said chute as the drum rotates and the mixing-blades drop their loads into said chute-section. This combined chute and its swinging section 5 are shown and separately claimed by me in my co-pending application Serial Number 697,289.

The delivery-drum 2 is of a hollow cylindrical form, and secured coaxially to the 55 rear face of the mixing-drum 1 with its forward axial opening coinciding with the rear axial opening of the mixing-drum. The rear face of the drum 2 has an axial opening 11 of greater diameter than its forward opening 12, so that when unmixed materials are dumped into the drum from a wheelbarrow over the transverse support 14, the materials will fall into the hollow of the drum near its circumferential periphery, 60 to be picked up by the turbinate delivery whirls or bodies 8 which are regularly arranged in a desired number around the axis of said drum.

The essence of this invention lies in the 70 peculiar form and function of these turbinate-form blades. Each blade 8 has one end secured to and across the inner face of the circumferential wall of the drum by means of rivets 16. From its said location of connection to the drum the said blade is twisted in such a way that it becomes whirled, forming a conical trough whose delivery vertex is within the mixing-drum 1 not far from the axis of the latter and protruding 75 through the axial opening 12 of the drum 2. The blades 8 thus have their coned or troughed delivery ends grouped centrally about the axis of the drum 1 and are seated about a cylinder 9 to which they are attached. The blades thus are adapted to deliver materials into the middle of the mixing-drum in a dry state, a certain amount of mixing taking place in the troughs of the blades as they rotate consonantly with the 80 drum 2. Water is conveyed into the center of the drum 1 by means of a pipe 10 which is passed through the central bore of the cylinder 9, and is supported by some fixed structure without the machine. 85

It will be seen that the peculiar whirled shape of the blades 8 taken together with the bringing of their delivery ends to a center, causes them when the drum is rotated, to pick up and transport unmixed materials 100 into the center of the drum 1 as rapidly as received from without. The use of a hopper is therefore obviated, and the operation thus simplified and made more efficient, besides conduced to a saving in the cost of 105 manufacture.

Having described my invention, what I claim as new, and desire to secure by Letters Patent, is:

1. In combination, a rotatable mixing-drum provided with axial inlet and outlet openings, and a delivery-drum secured thereto coaxially and provided with inlet and outlet openings with its outlet opening in registration with the inlet opening of the mixing-drum, said delivery-drum containing a plurality of open whirled plates arranged annularly about its circumferential wall and adapted to project into and deliver into the interior of said mixing-drum through said central registering openings.
2. In combination, a rotatable mixing-drum provided with axial inlet and outlet openings, and a delivery-drum secured thereto coaxially and provided with inlet and outlet openings with its outlet opening in registration with the inlet opening of the mixing-drum, said delivery-drum containing a plurality of open whirled plates arranged about its inner circumferential wall with their receiving ends attached to said wall and their delivery ends brought toward and arranged closely together about the axis of the drums and projected a con-

siderable distance through said registering openings to deliver into the mixing-drum approximately into the center thereof.

3. In combination, a rotatable mixing-drum provided with both axial inlet and outlet openings, a delivery-drum secured thereto coaxially and provided with both axial inlet and outlet openings with the outlet opening in registration with the inlet opening of the mixing-drum, said delivery-drum containing a plurality of open whirled turbiniform bodies inclined from the circumferential wall toward and closely grouped about its axis and projecting a considerable distance within the mixing-drum to deliver into the interior of said mixing-drum, an axially orificed ring upon which the inwardly-directed delivery ends of said whirled plates are mounted and means for conveying a liquid between the delivery-ends of said bodies through the hollow of said orificed ring into said mixing-drum.

Signed at Waterloo, Iowa, this 7th day of May, 1912.

THEODORE AHLBORN.
